Inventor:
Aloysius C. Lippert
By: Carl S. Lloyd

Atty.

UNITED STATES PATENT OFFICE.

ALOYSIUS C. LIPPERT, OF KENOSHA, WISCONSIN, ASSIGNOR, BY MESNE ASSIGNMENTS, TO THE NORLIPP COMPANY, OF CHICAGO, ILLINOIS, A CORPORATION OF ILLINOIS.

DESIGN FOR A RADIATOR CAP.

Application filed December 9, 1925. Serial No. 15,701. Term of patent 7 years.

To all whom it may concern:

Be it known that I, ALOYSIUS C. LIPPERT, a citizen of the United States, residing at Kenosha, in the county of Kenosha, and State of Wisconsin, have invented a new, original, and ornamental Design for a Radiator Cap, of which the following is a specification, reference being had to the accompanying drawing, forming a part thereof.

On the drawing,

Figure 1 is a front elevational view of the cap; and

Figure 2 is a top plan view of the cap.

I claim:

The ornamental design for a radiator cap as shown.

ALOYSIUS C. LIPPERT.
